UNITED STATES PATENT OFFICE.

IRA C. WIGHTMAN, OF NORWICH, NEW YORK.

ACETYLENE-GAS GENERATOR.

SPECIFICATION forming part of Letters Patent No. 641,059, dated January 9, 1900.

Application filed April 20, 1899. Serial No. 713,735. (No model.)

To all whom it may concern:

Be it known that I, IRA C. WIGHTMAN, of Norwich, in the county of Chenango, in the State of New York, have invented new and 5 useful Improvements in Acetylene-Gas Generators, of which the following, taken in connection with the accompanying drawings, is a full, clear, and exact description.

My invention relates to acetylene-gas generators.

My object is to produce an improved generator and a seal of oil or other non-freezable medium or liquid having an improved device for feeding the water to the calcium carbid;

15 an improved carbide-holder comprising a series of pockets connected in series and consecutively filled with water, said connections being trapped, means being also provided for operating the feed-water valves, as well 20 as the safety-valve, by the rise or fall of the gasometer.

It is constructed as follows, reference being had to the accompanying drawings, in which—

25 Figure 1 is a vertical section of the generator and gasometer, partly in elevation. Fig. 2 is an enlarged vertical section of the generator. Fig. 3 is a top plan of the carbide-holder. Fig. 4 is a sectional detail showing 30 the trapped connection between the pockets.

A is a suitable casing comprising sides or walls and a tight bottom. An air and gas tight drum 2 is erected within said casing, creating a narrow sealing-chamber 3 between 35 its walls and those of the casing, in which a suitable non-freezable liquid medium or agent, as a suitable oil, is placed. Into this sealing-chamber and sealing medium the gasometer 4 is inverted and guided in its vertical movements by the guide-bars and rollers in the usual way. None of the sealing medium or gas enters the drum. Upon said casing a suitable water-tank 5 is suitably mounted, having a discharge pipe and valve 6 opening 40 into a suitable water-tight auxiliary water-tank 7, provided with an eduction pipe and valve 8. The stem of each of these valves is provided with an arm or lever 9, both pivoted upon a connecting-rod 10, which is suitably 45 connected to a rod 11, secured at one end to the gasometer, whereby the fall of said gasometer will simultaneously open both valves

to permit water to flow through said pipes and auxiliary tank, and its rise above a certain point will close both of said valves. This 55 auxiliary tank 7 is normally always full of water, so that a discharge flow will start the instant the valves are opened; also, if the valve 6 should become leaky it cannot do any damage so long as valve 8 is tight, and if the 60 valve 6 should be tight and the valve 8 leaky then the tendency to create a vacuum in it will substantially prevent the flow of any water therefrom. It therefore prevents accidental leakage of water to the carbide when 65 the flow is supposed to be cut off.

The generator B comprises a suitable casing 12, a vessel 13, inverted and sealed therein, and a carbide-holder 14 within said casing and vessel and comprising a series of pockets for 70 separately receiving carbide (marked a, b, c, d, e, h, i, and k,) grouped or arranged about a central tube 15, through which the water-feed pipe 16 is conducted, as well as the gas-education pipe 17. The water is fed into the compartment or pocket a, and when it is filled to a fixed limit overflows through a trapped pipe 18 into the pocket b, and in this manner the carbide is successively used up in several pockets. This pipe 17 conducts the gas into the 80 chamber 19 in the gasometer, and 20 is the pipe conducting it to the burners.

A suitable valve 21 in the pipe 18 is provided with a handle or lever 22, which normally engages with the top of the cover over 85 the carbide-holder, so that said cover cannot be removed to permit access to said holder without swinging said lever out of the way, and this will close the valve 21 and prevent gas from escaping from the gasometer. 90

A pipe 23, connected to the pipe 20, is provided with a suitable lever-valve 24, with which an arm 25 on the gasometer engages in such manner that the rise of the gasometer above a certain point will open said valve to 95 permit the escape out of doors of the surplus gas until the pressure is reduced to safety. By closing the valve 25 in the pipe 20 the gas is shut off from the burners, and also if the valve 24 is then opened the gasometer can be 100 substantially emptied.

The gas-education pipe 17 passes for a part of its length through a box 27, and a drip-nozzle 26 on said pipe is duly sealed therein,

whereby all of the condensation and other impurities flow out onto said box.

What I claim as my invention, and desire to secure by Letters Patent, is—

- 5 An acetylene-gas generator, comprising a casing adapted to contain water, a bell in said casing, a carbid-holder situated in said casing beneath the bell, the said carbid-holder comprising an outer shell, a central tube, and
10 partitions between them creating multiple segmental carbid-holding compartments connected by openings through said partitions and pipes therein leading down nearly to the bottom of each compartment, except the one

first receiving the water and curved upward, 15 a feed-water pipe extending upward through said tube and feeding water into the primary compartment, and a gas-education pipe extending downward from the gas-chamber above said carbid-holder through said tube 20 and conducting it to a gasometer.

In witness whereof I have hereunto set my hand this 17th day of April, 1899.

IRA C. WIGHTMAN.
